CLAIM

The ornamental design for a wireless plug in gas detector as shown and described.

DESCRIPTION

FIG. 1 is a top perspective view of a wireless plug in gas detector showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view thereof; and,

FIG. 9 is an exploded top perspective view of the wireless plug in gas detector.

The broken lines in the drawings depict portions of the wireless plug in gas detector that form no part of the claimed design.
